US00D951712S

(12) **United States Design Patent** (10) Patent No.: **US D951,712 S**
(45) Date of Patent: **** May 17, 2022**

(54) **DRINKING FLASK**

(71) Applicant: **PI-Design AG**, Triengen (CH)

(72) Inventor: **Jorgen Bodum**, Meggen (CH)

(73) Assignee: **PI-DESIGN AG**

(**) Term: **15 Years**

(21) Appl. No.: **29/729,328**

(22) Filed: **Mar. 25, 2020**

(30) **Foreign Application Priority Data**

Oct. 7, 2019 (WO) WIPO88135

(51) **LOC (13) Cl.** **07-01**

(52) **U.S. Cl.**

USPC **D7/510; D7/511**

(57) **CLAIM**

The ornamental design for a drinking flask, as shown and described.

DESCRIPTION

FIG. 1 is a perspective view of a drinking flask showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the drawings depict portions of the drinking flask that form no part of the claimed design.

1 Claim, 7 Drawing Sheets
